UNITED STATES PATENT OFFICE.

EDWARD P. SCHAEFER, OF ROCHESTER, NEW YORK.

HEATING AND VENTILATING ATTACHMENT FOR CHIMNEY FLUES.

Application filed March 19, 1921. Serial No. 453,820.

To all whom it may concern:

Be it known that I, EDWARD P. SCHAEFER, a citizen of the United States, and resident of Rochester, in the county of Monroe and State of New York, have invented certain new and useful Improvements in Heating and Ventilating Attachments for Chimney Flues, of which the following is a specification.

10 The present invention relates to chimney flues and an object thereof is to provide a chimney flue with an improved means by which a room may be heated and ventilated from such flue.

15 To this and other ends the invention consists of certain parts and combinations of parts, all of which will be hereinafter described, the novel features being pointed out in the appended claims.

20 In the drawing:

Fig. 1 is a face view of the heating and ventilating attachment;

Fig. 2 is a face view with the grille plate removed;

25 Fig. 3 is a section on the line 3—3, Fig. 1;

Fig. 4 is a detail sectional view showing the manner in which the valves are guided;

Fig. 5 is a perspective view of one of the valves; and

30 Fig. 6 is a perspective view of the other valve.

Referring more particularly to the drawing, 1 indicates a chimney which has the usual passage 2 extending therethrough. In 35 one wall of the chimney an opening is provided in which is inserted a chambered member 3 having a surrounding flange 4 at its front for abutting the front face of the chimney. A grille plate 5 may be secured 40 over the front face of the chambered member in engagement with the flange 4.

The chambered member 3 has vertical side walls 6 extended across the flue and is substantially of the width as the flue. A flange 45 7 flush with the front face of the flue is provided on the bottom wall of the chamber and on the side walls 6.

The opposite inner faces of the side walls of the chambered member are provided with 50 horizontal guides 9, in this instance, two guides being provided on each side wall. On these guides operate valves, each comprising a horizontal portion 10 of slightly greater length than the flue passageway 2, 55 and a vertical portion 11 at the inner end of the horizontal portion 10. The horizontal

portion operates on the guides, while the vertical portion is adapted to cooperate with the flange 7. The vertical portions 11 of the two valves, when both are cooperating with the flanges 7, close the opening between the chamber 8 and the flue passageway 2 so that the flue passageway is unobstructed by the valves. When the valves are moved inwardly to their innermost positions, the 60 horizontal portions 10 will lie across the flue passageway 2, but a passageway will be provided around the forward edges of the horizontal portions 10 between the two portions of the flue on opposite sides of the valves. 65 The valves are independently adjustable and this adjustment may be effected by providing each of them with an opening 12 in its horizontal portion in which a hook member 13 may be engaged for the purpose of 70 shifting such valves.

It is apparent that either or both valves may be opened or closed either wholly or partially. This arrangement provides for the ventilation of a room through the chimney flue when the heating apparatus which connects with the flue is not throwing off gas. Should gas be passing through the flue, the chamber 8 may be closed to the flue passageway. It is also possible to conduct 80 heat from the furnace flue into the room after the gas has been driven off the heating apparatus. Furthermore, when the chamber 8 is closed to the flue, the valves 11 will become heated and will throw heat into the 85 room.

From the foregoing it will be seen that there has been provided a heater and ventilator of simple construction which may be readily attached to a chimney flue and easily 90 operated to ventilate a room or heat the same.

What I claim as my invention and desire to secure by Letters Patent is:

1. The combination with a chimney having a passageway therethrough, of a chamber opening to the exterior of the chimney and lying to one side of the passageway through said chimney and communicating with the passageway, of means movable to 100 close said chamber to the passageway or to open said chamber to the passageway above and below the chamber.

2. The combination with a chimney flue and a chamber extending through a wall 110 thereof, of a slide valve having a horizontal portion, and a vertical portion at the inner

edge of the horizontal portion, the horizontal portion being adapted when in its innermost position to bridge the flue passageway, and when in its outermost position, 5 to lie in the chamber and carry the vertical portion to a position where it will substantially form a continuation of the front wall of the flue passageway.

3. The combination with a chimney flue 10 and a chamber extending through a wall thereof, of a plurality of horizontally movable valves, each having a horizontal portion and a vertical portion, the vertical portions being adapted, when the valves are moved outwardly, to close the chamber to 15 the chimney and the horizontal portions being adapted, when the valves are moved inwardly, to bridge the flue passageway.

4. The combination with a chimney having 20 a passageway therethrough, and a chamber opening to the exterior of the chimney and arranged entirely to one side of the passageway through the chimney, of means closing the chamber to the passageway and 25 movable to bridge the passageway to open

the chamber to the passageway and to provide a passageway through the chamber from the passageway below the chamber to the passageway above the chamber.

5. The combination with a chimney having 30 an opening in one wall thereof, of a chambered member arranged in said opening and having a grille at its front and flanges at its rear projecting into the flue passageway, horizontal guides formed on 35 the opposite vertical walls of the chamber and the flanges, valves operating on said guides, each valve comprising a horizontal portion, and a vertical portion at the inner edge of the horizontal portion, the vertical portions being adapted to close the chamber to the flue passageway and the horizontal portions being adapted to bridge the flue 40 passageway when the valves are in their innermost positions, while providing a connection through the chamber between the flue passageway below the chamber and the flue passageway above the chamber. 45

EDWARD P. SCHAEFER.
